(57) **CLAIM**

The ornamental design for a bottle, as shown and described.

DESCRIPTION

FIG. 1 is a front perspective view of a bottle showing my new design;

FIG. 2 is a front view of the bottle of FIG. 1;

FIG. 3 is a rear view of the bottle of FIG. 1;

FIG. 4 is a left side view of the bottle of FIG. 1;

FIG. 5 is a right side view of the bottle of FIG. 1;

FIG. 6 is a top view of the bottle of FIG. 1; and,

FIG. 7 is a bottom view of the bottle of FIG. 1.

The features shown in broken lines are for the purpose of illustrating portions of the bottle that form no part of the claimed design.
